PAGE 2

Figure 1 is a side elevational view of a miniature passenger-carrying train showing my new design;

Figure 2 is an enlarged side elevational view of the middle car shown in Fig. 1;

Figure 3 is an enlarged perspective view of the locomotive shown at the left of Figure 1;

Figure 4 is a front view thereof;

Figure 5 is an enlarged perspective view of the rear car shown at the right of Figure 1;

Figure 6 is a rear view thereof.

The side not shown has substantially the same appearance as the side shown in the figures.

I claim:

The ornamental design for a miniature passenger-carrying train, substantially as shown and described.
